UNITED STATES PATENT OFFICE.

WILLIAM N. BALLARD, OF KANSAS CITY, KANSAS, ASSIGNOR OF ONE-HALF TO JAMES S. CUMMINS, OF KANSAS CITY, KANSAS.

DRY-PIPE VALVE MECHANISM.

1,325,358.

Specification of Letters Patent. Patented Mar. 30, 1920.

Application filed May 15, 1918. Serial No. 234,803.

To all whom it may concern:

Be it known that I, WILLIAM N. BALLARD, a citizen of the United States, residing at Kansas City, in the county of Wyandotte 5 and State of Kansas, have invented certain new and useful Improvements in Dry-Pipe Valve Mechanisms, of which the following is a specification.

This invention relates to automatic dry 10 pipe valve mechanisms of the type used in automatic sprinkler systems, in which air under pressure is utilized to normally retain water under greater pressure from filling the sprinkler system until a fire occurs and opens 15 one or more sprinkler heads.

Accordingly I provide an improved angular arrangement of air and water valves so positioned and connected as to obtain the requisite differential action for holding said 20 valves normally upon their seats.

It is also sought to provide an improved anti-water-column valve structure adapted to prevent reseating of the water valve after the latter has been opened, said water valve 25 in turn acting, when in seated position, to maintain said anti-water-column valve open.

Other features will hereinafter appear, and in order that the invention may be fully understood reference will now be made to 30 the accompanying drawing, in which:

Figure 1 is a vertical sectional view of one form of valve.

Fig. 2 is a vertical sectional view of another form of valve.

Referring now in detail to the various 35 parts, 1 designates the valve casing having upper and lower flanges 2 and 3, respectively, whereby it is connected to the sprinkler system. Access is had to the interior mechanism of the valve through a hand hole 5 in one side of the casing, which is normally closed by a face plate 7.

The valve casing is divided into a lower 40 water chamber 9, an upper air chamber 11, and an intermediate chamber 13 by the water valve 15 and the air valve 17. The air chamber 11 has an extension 20 at one side bounded on top by an arcuate wall 22 and the back by an inclined wall 24, to receive 50 the valves 15 and 17 when in the open position disclosed by dotted lines.

The valves 15 and 17 normally rest upon 55 separate seats 26 and 28 surrounding ports 30 and 32, respectively, with a flexible gasket 14 between the upper valve and its seat through

which the water flows to the sprinkler system should a fire occur. The valve 15 is of less diameter than the port 32 to pass therethrough when the valves open. The valve 17 is connected at its margin to the casing 1 by 60 a pivot 34 and has an intermediate depending leg 36 connected by a pin 37 to a lug 38 on the intermediate upper portion of the valve 15.

As shown on Fig. 1, the valves 15 and 17 65 are arranged at an acute angle to each other, with the valve 15 pivotally supported by the pin 37 for limited swinging movement about an axis parallel to the plane of the valve 17. This arrangement brings the valves in close 70 relation to each other and causes a portion of the valve 15 to project above the lower face of the valve 17, which is provided with a recess 40 to receive said portion of the valve 15 and also a portion of the valve 75 seat 26.

42 designates a small anti-water column valve arranged within the intermediate chamber 13 and connected at its margins to the interior of the valve casing 1 by a pivot 80 44. Said valve 42 has a seat 46 extending through the valve casing 1. A drain pipe 49 leading to a sewer is connected to the seat 46 to carry off any water which may leak past the valve 15 into the intermediate chamber 85 13. For this purpose the valve 42 is normally held in open position by a lip 51 on the valve 15.

Connected to the valve casing 1 at the air 90 chamber 11 is an air supply pipe 53 provided with a valve 54, and connected to the casing 1 at the water chamber 9 is a drain pipe 56 provided with a valve 57. The intermediate chamber 13 has a connection 16 leading to a fire alarm system, not shown.

In practice, sufficient air is forced into the air chamber 11 through the pipe 53 to hold the valves 17 and 15 closed against the water pressure exerted against the valve 15. In case the air pressure in the system above the 100 valve 17 becomes reduced as in the case of a fire which opens one or more of the sprinkler heads, that part of the water pressure that tends to open the valves will cause the valve 15 to open and swing the valve 17 therewith 105 to the dotted line position. As the valve 15 swings open it releases the small valve 42 which immediately becomes seated and prevents the valves 15 and 17 from reseating. When the purpose of the water has been ef- 110.

fected, the water supply is shut off, following which the valve 57 is opened to drain out all water in the system above the lowermost portion of the seat 26. The valves 57, 15 and 17 are then closed after which air is forced into the system through the pipe 53 until the desired air pressure is obtained above the valve 17. When lowering the valve 15, the valve 42 is raised so that the valves 15 and 17 may meet their respective seats.

In some instances when the valves open they fall backward to their seats and they are however prevented from becoming seated by a lug 60 on the valve 42 which engages 15 the lip 51 and prevents the valves 15 and 17 from completely closing, whereas if the valves 15 and 17 were permitted to become seated with equal pressure in upper and lower chambers they would become water- 20 columned due to the differential of the valves.

With the valves 15 and 17 arranged as shown, full pressure of the water is exerted against the underside of the valve 15 and tends to open the same, which pressure may 25 be represented by a dotted line drawn through the pin 37, and is transferred through said pin to the valve 17 at a point central thereof. Only one component of the water pressure is effective in reacting against 30 the air pressure, the other component being exerted in a line parallel with the direction indicated by the dotted line *b* drawn through the pivot 34. Said line *b* indicates the obliqueness of the valve 17 with relation to 35 the direction in which the water pressure acts and it will be understood by the obliqueness of the dotted lines *a* and *b* that a considerable part of the water pressure exerted on the valve 17 acts on a line connecting pin 37 with pivot 34 and against the latter pivot, and is therefore ineffective to open 40 valve 17, the remaining component of the pressure being active to open the valve when the air pressure is reduced. In this respect 45 the principle of operation is similar to that which characterizes the devices described in Patents Nos. 1,180,817 and 1,208,452, issued April 25th, 1916, and December 12th, 1916, respectively, in respect to which devices the 50 present device is an improved and more completely commercialized form.

The proportion of force thus transmitted to the pivot 34 and thus to the casing may of course be varied as desired by simply varying, within proper limits, the angularity of the valve seats 26 and 28.

In the modified form disclosed by Fig. 2, the principle of the construction is similar to that of the structure already described, 55 the corresponding parts being indicated by corresponding reference numerals with exponents, the chief difference being that the valves 17^a and 15^a and their valve seats are arranged in an angular relation the reverse 60 of that obtaining in the preferred form of

construction. The principle of the operation remains the same in all essentials.

Having thus described my invention, what I claim and desire to secure by Letters Patent, is:

1. A dry pipe valve mechanism comprising a casing having air and water chambers separated by an intermediate chamber, and pivotally connected air and water valves controlling communication between said chambers, said intermediate chamber being provided with an outlet passage and an anti-water-column valve movable to close said outlet passage, said last-named valve and one of the other valves being arranged 75 so that their paths of movement intersect, whereby said valves reciprocally obstruct each other's closing movements.

2. A dry pipe valve mechanism comprising a casing having an air chamber and a 85 water chamber and an intermediate chamber provided with upper and lower valve seats arranged at an angle to each other adjacent said air and water chambers, respectively, said intermediate chamber being 90 provided with a water outlet passage, an air valve pivotally connected with the casing and adapted to close the upper valve seat, a water valve pivotally carried by said air valve and adapted to close the lower 95 valve seat, and an anti-water-column valve associated with said water outlet passage and mounted for movement in a path intersecting the path of movement of said water valve, the angular relation of said air and 100 water valve seats being such that the force tending to open said water valve is rendered partially ineffective for opening the air valve by a component thereof being exerted thereon along a line connecting the pivots of said 105 air and water valves.

3. A dry pipe valve mechanism comprising a casing having an air chamber and a water chamber and an intermediate chamber provided with upper and lower valve seats 110 arranged at an angle to each other adjacent said air and water chambers, respectively, a pivotally movable air valve adapted to close said upper seat, and a water valve pivotally carried by said air valve and adapted to 115 close said lower seat, said intermediate chamber being also provided with an outlet passage and an anti-water-column valve movable to close said outlet passage, said last-named valve and said water valve being arranged so that their paths of movement intersect, whereby said valves reciprocally obstruct each other's closing movements.

4. A dry pipe valve mechanism comprising a casing having an air chamber, a water 125 chamber, and an intermediate chamber provided with upper and lower valve seats arranged at an angle to each other adjacent said air and water chambers, respectively, a pivotally movable air valve adapted to close 130

said upper seat, and a water valve pivotally carried by said air valve and adapted to close said lower seat, said intermediate chamber being also provided with an outlet 5 passage and with an anti-water-column valve movable to close said outlet passage, said valves being arranged so that the path of movement of the anti-water-column valve intersects the path of movement of one of 10 the other valves, whereby the valves having the intersecting paths of movement reciprocally obstruct each other's closing movements.

5. A dry pipe valve mechanism comprising 15 a casing having an air chamber, a water chamber, and an intermediate chamber provided with upper and lower valve seats arranged at an angle to each other adjacent said air and water chambers, respectively, a 20 pivotally movable air valve adapted to close said upper seat, and a water valve pivotally carried by said air valve and adapted to close said lower seat, said intermediate chamber being also provided with an outlet passage 25 and with an anti-water-column valve movable into position to close said outlet passage, said water valve having a projecting portion engaging said anti-water-column valve and normally retaining the latter in 30 open position, and said anti-water-column valve having a portion projecting, when said anti-water-column valve is closed, into position for obstructing the reseating movement of said water valve.

6. A dry pipe valve mechanism comprising 35 a casing having an air chamber and a water chamber and an intermediate chamber provided with upper and lower valve seats arranged at an angle to each other adjacent said air and water chambers, respectively, 40 and with a portion of the lower seat projecting within and through the plane of the other seat, an air valve adapted to close the upper seat and pivotally connected with the casing and provided with a depending leg, a 45 water valve adapted to close the lower seat and provided with a pin connecting said water valve with said leg for limited pivotal movement about an axis parallel with the plane of said upper valve seat, said intermediate chamber being provided with a water outlet passage, and an anti-water-column valve 50 associated with said water outlet passage and mounted for movement in a path intersecting the path of movement of said 55 water valve, the angular relation of said air and water valve seats being such that the force tending to open said water valve is rendered partially ineffective for opening the air valve by a component thereof being 60 exerted thereon along a line connecting the pivots of said air and water valves.

In testimony whereof I affix my signature, in the presence of two witnesses.
